UNITED STATES PATENT OFFICE.

ARTHUR J. WEST, OF BETHLEHEM, PENNSYLVANIA.

VALVE FOR GAS COMPRESSORS AND PUMPS.

1,052,540.

Specification of Letters Patent. Patented Feb. 11, 1913.

Application filed July 12, 1911. Serial No. 638,132.

To all whom it may concern:

Be it known that I, ARTHUR J. WEST, a citizen of the United States, residing at Bethlehem, in the county of Northampton and State of Pennsylvania, have invented 5 certain new and useful Improvements in Valves for Gas Compressors and Pumps, of which the following is a specification.

This invention relates to discharge valves 10 for air or other gas compressors, and particularly to a valve of the combined mechanically operated and automatic type. In such valves the valve member proper is moved to its closing position by a positively operated plunger directly or through 15 the medium of an interposed air cushion. The valve is subsequently released by the plunger so as to be permitted to open when the total outward pressure predominates 20 sufficiently over the inward pressure to overcome the friction and inertia of the valve. These are often great enough to require an undue predomination of such pressure resulting in a deranged valve action 25 and a consequent loss of efficiency. In a co-pending application filed July 12, 1911, Serial No. 638,133, I have described a mechanism in which this difficulty is overcome 30 by causing the plunger to exert a retractile force upon the automatic or floating valve.

The purpose of the present invention is to secure a similar result by a different means, consisting essentially in a construction in which the area of the floating valve 35 subjected to cylinder pressure acting in an opening direction is made greater than the area of that valve exposed to discharge pressure acting in a closing direction, and an area equal to the difference between the 40 above named areas is exposed to atmospheric pressure acting in a closing direction. Thus the opening tendency during the discharge stroke is increased so as to overcome friction and inertia.

45 The invention will be described in connection with the accompanying drawing, in which:

Figure 1 is a vertical section through a discharge valve showing the valve ready to 50 open; and Fig. 2 is a similar view showing the position assumed by the parts when the valve has opened.

In the drawings, 1 represents the walls of the cylinder head and 2 the discharge passage 55 formed in the cylinder head.

3 indicates a point within the cylinder.

4 is the valve operating rock shaft which may be rocked in any suitable manner. The rock shaft carries the usual rocker arm 5 connected by a link 6 to the plunger 7. 60 This plunger is guided in a bonnet 8 held by studs and nuts 9 to the cylinder head. The studs 9 also pass through a flange on the valve cage 10, which is closely fitted in suitable openings in the cylinder head walls 65 and is provided with a series of ports 11 and 12, as clearly shown in the figures.

The floating valve 13 slides in the valve cage 10. It is of the piston type and is provided with a metallic packing ring 14 so 70 that in the closed position of the valve, as shown in Fig. 1, a tight joint is made. This floating valve 13 consists of an imperforate head 15 having two coaxial cylindrical extensions or shells 16 and 17 attached thereto. The outer shell 16 is provided with ports 18 for a purpose later to be described, and is provided at its end with a rim or flange 19. The bore of the cage 10 is of 75 two diameters, the smaller of which is 80 closely fitted by the main walls of the shell 16, while the flange 19 makes a close fit in the larger bore. From this results the formation of a pocket 20, in which, in the closed position of the valve, air is trapped 85 to form a cushion and bring the valve quietly to rest. The plunger 7 is tubular in form and open at its outer end while at its inner end it carries an annular head 21 closely fitting in the annular space between 90 the shells 16 and 17, a tight joint being made with each of said shells by means of the packing rings 22 and 23.

Considering the valve in the position shown in Fig. 1, it will be seen that the 95 floating valve 13 is subject to pressure within the cylinder over its entire head 15, such pressure acting in the opening direction. In opposition to this opening pressure it is acted upon by atmospheric pressure 100 over the entire area within the cylindrical shell 17, while the annular area outside of the shell 17 is subject to discharge pipe pressure entering through the ports 18. By varying the relative areas within the shell 105 17 and the annular area outside such shell the valve may be given any desirable opening tendency. The ports 18 are placed at some distance from the head end of the valve so as to be overtraveled by the head 21 of the 110 plunger 7, thus creating an air pocket or cushion which will prevent actual physical

contact between the head of the plunger 7 and the floating valve.

With this statement of the construction, the operation of the valve can now be traced out. Assuming the valve to be in the position of Fig. 1, the piston of the pump will be moving toward the right. The plunger 7 is shown as near the right hand limit of its motion. The opening pressure exerted 5 upon the valve will increase until it is sufficient to preponderate over the closing pressure and the friction and inertia of the valve. Knowing the discharge pressure and the other characteristics of the pump this 10 may be readily proportioned so that the valve will open ports 11 when the pressure in the cylinder is substantially equal to the discharge pressure. Assuming such preponderance to be attained the valve 13 will 15 quickly move to the position shown in Fig. 2, being gently brought to rest by the air cushion between the plunger and valve. By 20 the time that the piston of the pump has reached the end of its stroke to the right 25 the rock shaft 4 and its connected mechanism will have moved the plunger 7 to the left thus forcing valve 13 through the medium of the air cushion interposed between the plunger and valve to its closed position, or if the pressure in the cylinder 30 should fall prior to such movement of the plunger 7 the valve 13 would automatically close. In either event the closing movement 35 of the valve is checked and cushioned by the air pocketed in the space 20. At the time the plunger 7 again moves toward the right the pressure in the cylinder will be so low that the valve 13 will be held closed by discharge pipe pressure, thus allowing 40 the plunger 7 to move to its right hand position, leaving the valve 13 closed. This cycle 45 of operations is repeated for each double stroke of the pump piston.

It is obvious that by varying the ratios between the areas exposed to cylinder, discharge and atmospheric pressures, the valve 50 may be caused to open either before, simultaneously with, or after the equalization of cylinder and discharge pressures, as conditions may require.

Having thus described the invention, what I claim is:—

1. In a discharge valve for gas pumps, the combination of a valve of the piston type adapted to be urged in its opening direction by pressure within the pump and in its closing direction by pressure acting over a part of its area assisted by a less pressure acting over the remainder of its 55 area; and a plunger adapted to move the valve to its closed position.

2. In a discharge valve for gas pumps, the combination of a valve of the piston type adapted to be urged in its opening direction by pressure within the pump and

in its closing direction by pressure acting over a part of its area assisted by a less pressure acting over the remainder of its area; an air cushion to check the closing movement of the valve; and a plunger adapted to move the valve to its closed position. 70

3. In a discharge valve for gas pumps, the combination of a valve of the piston type adapted to be urged in an opening direction by pressure within the pump and in a closing direction by discharge pressure acting over a portion of its area assisted by a less pressure acting over the remainder of its area; and a plunger adapted to move the valve to a closed position by the medium of an interposed air cushion. 80

4. In a discharge valve for gas pumps, the combination of a valve adapted to be urged in its opening direction by pressure within the pump and in its closing direction by discharge pressure acting over a part of its area assisted by a less pressure acting over the remainder of its area; and a plunger adapted to move the valve to its 90 closed position.

5. In a discharge valve for gas pumps, the combination of a valve adapted to be urged in an opening direction by pressure within the pump and in a closing direction by discharge pressure acting over a portion of its area assisted by a less pressure acting over the remainder of its area; and a plunger adapted to move the valve to a closed position by the medium of an interposed air 95 cushion. 100

6. In a discharge valve for gas pumps, the combination of a valve subject to pressure within the pump and consisting of a head having two cylindrical shells attached thereto, the outer shell having ports whereby the annular space between the shells is subject to discharge pressure; a cylindrical plunger adapted to act as a piston in the annular space between the shells, such plunger being so formed as to permit atmospheric pressure to act against the valve within the inner shell; and means for actuating the plunger to alternately close and release the valve. 110

7. In a discharge valve for gas pumps having a discharge passage, the combination of a ported valve cage mounted to communicate with the pump and with the discharge passage; a piston valve movably mounted in the valve cage and consisting of a head portion and two coaxial cylindrical shells attached thereto, the outer shell having ports whereby the annular space between the shells is subject to discharge pressure; a plunger adapted to act as a piston in the annular space between the shells, such plunger permitting communication between the atmosphere and the portion of the valve within the inner shell; and means for 120 125 130

actuating the plunger to alternately close and release the valve.

8. In a discharge valve for gas pumps having a discharge passage, the combination 5 of a ported valve cage mounted to communicate with the pump and with the discharge passage; a piston valve movably mounted in the valve cage and consisting of a head portion and two coaxial cylindrical shells 10 attached thereto, the outer shell having ports whereby the annular space between the shells is subject to discharge pressure; an air cushion adapted to check the closing movement of the valve; a plunger adapted

to act as a piston in the annular space 15 between the shells, such plunger permitting communication between the atmosphere and the portion of the valve within the inner shell; and means for actuating the plunger to alternately close and release the valve. 20

In testimony whereof I have signed my name to this specification in the presence of two subscribing witnesses.

ARTHUR J. WEST.
